UNITED STATES PATENT OFFICE

2,278,732

INSULATING BUILDING STRUCTURE

Joseph R. Parsons, Chicago, Ill., assignor to
 United States Gypsum Company, Chicago, Ill.,
 a corporation of Illinois

Application April 22, 1940, Serial No. 330,891

3 Claims. (Cl. 20—4)

This invention relates to insulating building structure and more particularly to flocculent fibrous insulating bats and their assembly in a wall structure whereby settling and sagging of the loosely matted fiber, and the consequent partial destruction of the insulating properties of the wall, is prevented.

The invention also relates to the manufacture of fibrous insulating bats particularly of mineral wool whereby they are substantially self-supporting when they are inserted between supports such as studding and also whereby they may be formed in rolls adapted for storing in superposed tiers without detrimental compression of the mineral wool or other harmful distortion of the bat or of any fabric covering which may form a part thereof.

It is an object to provide an insulating bat having resilient means associated therewith whereby it is only necessary to place the bat in position between the studding and flex the resilient means during positioning of the bat whereby the bat is permanently supported between the studding by the flexed engagement of the resilient means therewith.

Fibrous insulating material, such, for instance, as mineral wool, when placed in the usual manner between the studding in a building structure, has a tendency to settle, particularly when moisture condenses therein, and this settling results in at least a partial destruction of the insulating qualities of the mineral wool. Various methods have been proposed for supporting fibrous insulating bats. For instance, a paper cover somewhat wider than the bat is sometimes secured thereto by means of asphalt cement or similar means, and the extending flaps of paper on each side of the bat are fastened to the studding by means of nails or the like. The usual procedure is to place strips of wood over the paper flaps and secure the strips by nails to thereby prevent tearing of the paper. This method of construction involves not only the use of nails and additional lumber, but also involves added labor in the erection process.

Difficulty has been experienced in the manufacture and storage of a fibrous mineral bat for insulating purposes. In many instances it is necessary that the warehouses of the manufacturers of mineral wool insulation should be several times the size of the actual production room. The reason for this is that it is impracticable to stack mineral wool bats one on top of another for storage for the reason that the compressive force exerted upon the lower bats tends

5 to permanently deform them and reduce the insulating efficiency thereof. Mineral wool bats are quite resilient, but not sufficiently so to completely return to their normal state after extended compression in storage.

It is, therefore, an object of this invention to provide mineral wool insulation bats which are capable of being superposed one upon another for storage purposes without appreciably impairing 10 their insulating qualities.

Another object is to provide a self-supporting preformed mineral wool bat having spaced flexible members or resilient elements extending across the bat at intervals along the length 15 thereof, with the flexible members of a length somewhat greater than the width of the bats, whereby the bats may permanently be supported between normally spaced studding merely by inserting the bat and flexing the elements to engage the sides of the studding.

Further objects will be apparent from the specification and the appended claims.

In the drawing:

Fig. 1 is a perspective view of a wall structure 25 including studding and wall covering and illustrates one of the self-supporting bats of this invention permanently supported between the studding.

Fig. 2 is a transverse sectional view through a 30 fibrous insulating bat and illustrates one embodiment of the invention.

Fig. 3 is a sectional view similar to Fig. 2, but with the resilient member protruding beyond each edge of the bat.

Fig. 4 illustrates another embodiment with a 35 resilient member and a fabric cover on opposite sides of the bat.

Fig. 5 illustrates one method of assembling the bats in the wall structure by flexing the resilient 40 member outwardly.

Fig. 6 is similar to Fig. 5 but illustrates a slightly different method of assembling the bat in the structure by flexing the resilient member inwardly.

Fig. 7 is a detail sectional view through one 45 of the flexible members assembled in a bat and illustrates one method of securing the flexible member between the mineral wool and the fabric cover.

Fig. 8 illustrates a slightly different embodiment in which the flexible member is embedded 50 in the bat.

Fig. 9 is a fragmentary detail view illustrating the bifurcated end of one of the flexible supporting members.

Fig. 10 illustrates one of the bats rolled for storage and the method of superposing one row upon another.

Referring to the drawing in detail, the embodiment illustrated in Fig. 1 comprises a wall structure in which are provided spaced studding 1 and sheathing or any suitable wall covering 2 secured thereon. The opposite side of the wall structure may also be provided with any suitable wall covering such as lath and plaster. A fibrous insulating bat 3 is positioned between the studding, and this bat is retained and supported by means of flexible strips or bars 4 which are slightly longer than the width of the bat and are preferably secured thereto so that their ends project slightly beyond the edges of the bat. In inserting the bat, it is only necessary to place it in position between the studding and then push inwardly on the flexible bars 4, which will then flex inwardly as shown in Fig. 6, and the ends of the bars, which may be sharpened or serrated, will engage the sides of the studding and will permanently secure and support the bat in position for effectively insulating the structure.

The strips or bars 4 or their equivalent may be formed of any suitable material such, for instance, as spring metal, bamboo, or various types of manufactured fiber.

In building structures of this type, the studding are usually spaced approximately 16 inches on centers. However, the space between the studding will vary between 14 and 15 inches, but normally will not exceed 15 inches. Therefore, the resilient bars 4 are preferably made approximately 15 1/4 inches long so that, when pressed between the studding, they will not unduly compress the fibrous pad, but will flex sufficiently to retain the pad firmly in place. It will, of course, be apparent that the bars may be made of any length in accordance with requirements.

Fig. 2 illustrates one method of securing the bars to the mat of the fibrous material. In this view a mat 5 of fibrous material, such as mineral wool, is provided on one side with a paper covering 6. This covering may be secured to the mineral wool in the usual manner, preferably by asphalt cement or the like, and the resilient bars 4 are transversely secured to the outside of the paper cover by any suitable means. For instance, they may be cemented thereto, and, in the particular embodiment shown in Fig. 2, the bars are flush with one edge of the mat, as shown at 7, and extend materially beyond the other edge of the mat, as indicated at 8.

The type of bat construction disclosed herein is particularly advantageous for storage purposes when the bats are rolled, as shown in Fig. 10, to provide a rolled unit 9 which may be stood on end so that the mat is supported by the bars 4 with the protruding ends 8 of the bars extended upwardly. When a tier of these rolls is placed on a warehouse floor, a sheet of fiber board or any other suitable rigid or semi-rigid panel 11 may be placed on top of the rolls and will be supported on the protruding ends 8 of the bars. Other rolls may then be placed on the panel 11 and the process may be continued for several tiers, the number of tiers depending upon the rigidity of the resilient bars 4 and the number of bars used. However, as these bats are comparatively light, a large number of tiers may be supported without damage to the bats.

Fig. 3 illustrates another method of securing the bars to the mineral wool bat. In this embodiment the bars 4a are similar to those illus-

trated in Figs. 1 and 2, but extend beyond each edge of the mat, as shown at 11. Also in this embodiment the fabric covering 8 is adhesively secured to one side of the mat and the bars are secured to the outer surface of the fabric in the manner previously described.

Fig. 4 illustrates another embodiment in which a fabric cover 12 is secured to one side of the insulating material 5 and the bars 4b are secured directly to the opposite side of the mat without any intervening paper covering thereon. The bars in this embodiment preferably extend beyond both edges of the bat. However, they may extend only beyond one edge, if desired. In this embodiment the bars may be secured directly to the fibrous material itself.

Fig. 5 illustrates one method of springing the bars between the studding. In this embodiment the central bulge or curvature of the bar is outwardly toward the workman inserting the bat, and it may be inserted by flexing the ends of the bar to enter between the studding and the resilience will cause the bar to tend to straighten out and it will permanently be retained between the studding and effectively support the bat.

In Fig. 6 the bulge or curvature of the bar is away from the workman, and this is a somewhat more convenient method of installation for the reason that it is only necessary to place the bat between the studding and push inwardly on the center of each bar.

Fig. 7 illustrates a slightly different embodiment in which the bars are secured between the fabric cover and the insulating mat. In this embodiment the bar 4c is first secured to a fabric cover 13 by means of a fabric clip 14, and the fabric cover 13, including the attaching bars, may then be secured to the mat 5 in the usual manner.

Fig. 8 illustrates still another embodiment and comprises a fibrous pad 15 which may or may not have a fabric cover. In this embodiment suitable flexible rods or bars 16 are inserted through the fibrous material itself and are supported thereby with their ends protruding as shown at 17. In this embodiment also, one end of each rod may be flush with the same edge of the bat if desired instead of protruding therefrom. The supporting bars are preferably sharpened at the ends in some manner in order to more effectively engage the studding. For instance, they may be pointed as shown at 18 in Fig. 1, or they may be serrated as at 19 (Fig. 9).

It is intended, of course, that the invention should not be limited to the specific embodiment or embodiments disclosed herein since many modifications may be made, and it is contemplated, therefore, by the appended claims to cover any such modifications as fall within the true spirit and scope of this invention.

Having thus described this invention, what I claim and desire to be secured by Letters Patent is:

1. The method of storing elongated bats of loosely matted mineral wool fiber comprising distributing a plurality of slender semi-rigid bars of slightly greater length than the width of said bats transversely at intervals along the length of each bat, rolling said bat to form a closed coil roll with said bars extending slightly from at least one end, and storing said rolls on end in a plurality of superposed tiers by interposing a tier-supporting panel between adjacent tiers.

2. An elongated insulating bat which is self-supporting when rolled and self-supporting when

unrolled and inserted between studding or the like, comprising an elongated, freely flexible, non-self-supporting mat of flocculent mineral wool, and a plurality of narrow, semi-rigid resilient bars spaced throughout the length of said mat and secured transversely thereof to form an integral part of said bat, said bars being slightly longer than the distance between said studding and being sufficient in number and rigidity so that when said bat is rolled it is self-supporting when the roll is stood on end, and sufficiently resistant to bending to support a large number of alternate separating panels and rolled bats thereon without material compression of said flocculent material.

15

3. An elongated flexible insulating bat capable of being formed into a compact roll, comprising an elongated mat of flocculent mineral wool, a covering sheet on at least one side of said mat, and a plurality of longitudinally spaced semi-rigid resilient bars extending transversely of said mat and permanently secured to the inside surface of said covering and of a length slightly greater than the width of said covering, said bars in each row being sufficiently rigid to support thereon a plurality of superimposed alternate panels and rolled bats for storage or shipment without materially compressing any of said bats.

JOSEPH R. PARSONS.
